UNITED STATES PATENT OFFICE

128,171

DESIGN FOR A MAGNIFYING UNIT

Albert D. Mizzy, New York, N. Y.

Application April 12, 1941, Serial No. 100,349

Term of patent 14 years

To all whom it may concern:

Be it known that I, Albert D. Mizzy, a citizen of the United States, residing at New York, in the county of New York and State of New York, have invented a new, original, and ornamental Design for a Magnifying Unit, of which the following is a specification, reference being had to the accompanying drawing, forming part thereof.

Fig. 2 is a side elevational view thereof; Fig. 3 is a bottom view of the same; and Fig. 4 is a perspective view thereof.

I claim:

The ornamental design for a magnifying unit, as shown.

ALBERT D. MIZZY.
